Primary Examiner — Karen E Kearney

(57) **CLAIM**

The ornamental design for a flash disk, as shown and described.

DESCRIPTION

FIG. 1 is a perspective view of a flash disk showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded perspective view thereof, shown with unclaimed environment; and,

FIG. 9 is another perspective view thereof, shown with different unclaimed environment.

The broken line showings in FIGS. 8 and 9 are for the purpose of illustrating environmental structure and form no part of the claimed design.

1 Claim, 8 Drawing Sheets
